FLUID-TIGHT PACKING FOR FLOATING-ROOF-
TYPE HYDROCARBON TANKSMaurice Mercier, 172 Boulevard du Montparnasse,
Paris, France

Filed Apr. 22, 1960, Ser. No. 24,158

Claims priority, application France Apr. 25, 1959
2 Claims. (Cl. 220—26)

As is well-known, one of the best methods of insuring proper preservation of hydrocarbons is by storing them in floating roof type tanks in which the major part of the cylindrical surface of the tank is covered by a circular sealed metal pontoon which floats on the liquid in storage.

The annular space comprised between the pontoon and the side of the tank is customarily occupied by a fluid-tight packing system, so that the entire free surface of the stored liquid is screened from all contact with the open atmosphere.

Packings resorted to hitherto consist either of metal scrapers which are applied by mechanical means against the fixed wall of the tank and are connected to the pontoon by resilient membranes, or of rubber packers of generally tubular shape which are applied both against the periphery of the pontoon and the inside of the wall by the resilient pressure exerted by a gaseous or liquid fluid.

In addition to this principal sealing device, floating roofs resorted to hitherto comprise a secondary seal the purpose of which is to prevent rainwater from penetrating into the product under storage.

The present invention has for its object a fluid-tight packing system in which an annular plastic membrane, shaped like a deep gutter, is applied against the side of the tank under the pressure exerted by a dense, spheroidal and granular filler material; furthermore, the shape of the gutter enables it to collect and drain away rainwater.

The advantage of the invention resides in the small membrane area which enters into its design, in the relative invulnerability of this membrane, the solid filler material of which cannot empty through a small hole as would be the case if a liquid filler were used, and, lastly, in the dual sealing role of this membrane with respect to the liquid and the stored gas on the one hand and the rainwater on the other.

The invention will be clearly understood from the following description given with reference to the accompanying drawings which illustrate, by way of example only and not in a limiting sense, various possible embodiments of the devices designed to allow the principles referred to hereinabove to be put into application.

In these drawings,

FIG. 1 is a sectional view of a fluid-tight device according to the invention.

FIG. 2 is a detail view of the method of assembling the membrane to its hoop.

FIG. 3 is a variant, in which the fluid-tight device is mounted on a pontoon having an inclined generating line.

FIG. 4 is a variant of a suspension device for the free rim of the membrane.

Referring now to the drawings, it will be seen that FIG. 1 is a partial section view in elevation of the tank, the pontoon and the fluid-tight packing. In this figure, the

2

wall of the tank is designated by the numeral 1, the bottom and top of the float by the numerals 2 and 3 respectively, the level of the liquid by the numerals 4 and 4' and the vertical wall of the float by the numeral 5.

5 The fluid-tight packing consists of a membrane 6 manufactured out of a molded sheet of rubber or plastic material. This membrane is fixed rigidly and in sealing fashion to the wall 5 of the float by means of bolts 7 which pass through notches 8 in a flange 9 welded in

10 hermetic fashion to the wall 5.

The free rim of the membrane is rendered rigid by a flat iron hoop 10 to which it is bolted. This flat hoop is of generally circular shape and may be expandable or non-expandable. The iron hoop and the membrane 15 which it reinforces are supported by means of inclined connecting rods 11—say one or two in number per yard of tank circumference—which are articulated at 12 and 13 respectively onto the hoop 10 and the wall 5 of the float. In consequence, the circular outer wall of the 20 gutter-shaped membrane 6 can be pressed against the side 1 by the horizontal reaction generated by the rods 11 under the effect of the gutter's weight characteristic and the friction forces set up between the membrane and the side.

25 The circular trough formed by the membrane is filled with a mass of dense and granular material 14 possessing as low internal cohesion characteristics as possible.

It will be appreciated that, similarly to the law governing the thrusting action of earth banked up against a 30 vertical wall, this mass of material will press the membrane against the wall 1 and, through the medium of the rods 11, the weight of this filler material will produce a reaction that will apply the upper rim of the membrane against the wall 1.

35 A bearing and supporting surface 15, which may be either flat and horizontal, or inclined, and which is integral with the wall 5, can be provided, if required, in order to insure improved application of the membrane 6 against the wall 1.

40 It will thus be appreciated that these various component elements together constitute a resilient fluid-tight packing which is integral with the float and which is pressed against the wall of the tank by the sideways thrust resulting from the falling-in action of the granular material.

45 Inside the gutter and by the horizontal reaction set up by the rods against the upper hoop, both of which will vary with the weight of the granular material.

With this device, the force with which the membrane is pressed against the wall is virtually independent of 50 movement of the float 2, 3, 5 with respect to the side 1 of the tank; moreover, such movement is authorized by the device without the fluid-tightness being affected.

The wall 1 is liable to accumulate rainwater, and this water which streams down the inner surface of 1 55 will be stopped by the rigorous manner in which the membrane 6 is applied against the wall 1 so that the rainwater spills into the gutter-shaped membrane, passing through the granular filler material in the process. This rainwater collects at the bottom of the gutter and 60 drains away via orifices 16 into which debouch drainpipes 17 which evacuate the water out of the metal pontoon, the water being thus drained away out of the tank in a manner well-known per se.

The connection effected between the pipes 17 of the

wall 5 and the membrane 6, at the location of the orifices 16, is a hermetic connection obtained by conventional methods, bolted flanges being an example.

It is to be clearly understood that the relative positions of the bottom of the float 2, the bottom of the membrane and its support 15, the orifices 16 of the sealing flange 9, as well as of the articulations 13 and 12, are illustrated by way of example only and that their exact positions will be determined according to the pressure which is required to be exerted by the membrane against the wall of the tank, the acceptable amount of residual water to be left over in the gutter and the requirements in respect of ease of access to and servicing of the various parts of the system.

FIG. 2 shows the method of fixing the top outer edge of the gutter-shaped membrane 6 to the hoop 10. This fixing is achieved by means of bolts 18 having large button heads 19 which stand proud of the rubbing face 20 of the membrane to the extent of about one or two millimeters. This optional arrangement provides a means of protecting the edge of the membrane against undue friction leading to wear.

FIG. 3 is a highly diagrammatic illustration of an embodiment of a fluid-tight packer which is in every way identical to that in FIG. 1 except that the peripheral wall 5 of the pontoon is of truncated-cone shape to permit better utilization of the granular filler material and to facilitate inspection and possible repairing of the membrane and its fixing members.

Moreover, by reason of its conical shape, the wall 5 embodies, at its bottom, a limiter of eccentricity with respect to the wall 1 of the tank.

FIG. 4 represents an embodiment in which the rods work in tension instead of in compression. The membrane, its rim flange, its fixing method and its filler material are identical to those in FIG. 1, but the rods 21, which are articulated at 22 and 23, respectively, onto the hoop 25 and onto brackets 24, connect the latter to the hoop 25 and operate in tension. The relative positions of the articulations 22 and 23 and the hoop 25 enable horizontal thrusts to be set up which act upon the latter in the requisite direction and with the required force, in accordance with the intended purpose.

In the fluid-tight packing executed according to FIGS. 1, 3 and 4, the gutter-shaped membrane can be constituted either in a single piece surrounding the whole of the pontoon or in a multiplicity of individual elements each of which corresponds to a section only of the circumference, these several elements being interconnected by means of fluid-tight seals and being interchangeable and easy to replace.

Clearly, the greatest hazard to be feared in the case of a tank containing hydrocarbons is fire.

In the case under consideration, such danger could arise through leaks occurring between the envelope or wall of the tank and the packing which is applied between the metallic floating roof and this envelope or wall. Such danger is very great if the membrane joining the metal float to the envelope comes to be destroyed by fire, since the flames can then spread to the annular space comprised between the metallic floating roof and the envelope of the tank.

Such a fire over a limited area can be successfully extinguished by producing at, or leading up to, the required spot a gas which is incapable of sustaining combustion (examples being carbon or sulphur anhydrides, nitrogen, etc.), in a quantity such that the inflammable hydrocarbon vapors are prevented from coming into contact with the air and its oxidizing properties. Moreover, it is well known that air ceases to be an oxidizer when mixed with 25% of inert gases.

According to the invention, the production of such gases is automatically insured in the event of fire breaking out in the tank by a decomposition of the material in the gutter, for, as is well known, certain carbonates and

other metal salts give off inert gases at relatively low temperatures, namely gases which are incapable of sustaining combustion.

By way of a non-limiting example of such a carbonate may be cited zinc carbonate $\text{CO}_3 \text{Zn}$ which decomposes at 140° C. into carbon anhydride CO_2 and zinc oxide ZnO , this being a product to be used in preference to others of a similar nature such as:

Basic carbonate of Pb:

Decomposition temperature: 180° C.

Carbonate of cadmium:

Decomposition temperature: 357° C.

Basic carbonate of copper

Decomposition temperature: 200° C.

In the natural state, carbonate of copper is known as "Malachite" and carbonate of zinc as "Smithsonite."

The above-mentioned carbonates can be utilized either in the form of small balls produced by breakage and subsequent abrasion in accordance with methods well-known per se, or in the form of balls molded by the addition of 25 a binding agent consisting of five to fifteen percent of some thermoplastic material such as vinyl chloride or polystyrene, or of some heat-hardenable material such as urea-formaldehyde or formol-formaldehyde resin.

Thus it will be appreciated that, if a certain quantity 30 of metal salts in the form of spheroidal elements is placed inside a floating-roof's fluid-tight packing the membrane of which is sufficiently refractory thanks to its reinforcing wire mesh or to the incorporation of non-burning materials, a large quantity of inert gas will be given off, 35 namely of gas incapable of sustaining combustion, and that moreover the gas will be given off precisely at the spot where the outbreak of fire occurs.

By way of example only and not in a limiting sense, it will be indicated that if the seal of a tank measuring 40 twenty meters in diameter be filled with carbonate of zinc, it is capable of giving off a two-meter-thick blanket of CO_2 by total decomposition within the free space of the reservoir.

Since this gas is emitted precisely at the seat of the fire, it is extremely effective.

It is to be clearly understood that the invention is by no means limited to the specific embodiments described hereinbefore, but that its scope encompasses all variants executed according to the same principles and in conformity with its spirit.

What I claim is:

1. A fluid tight seal between a peripheral wall of a tank and a peripheral wall of a floating roof of the tank and comprising, in combination, a plurality of arms each hingedly connected at one end thereof to said roof and extending from said attached end toward the peripheral wall of said tank;

60 a substantially rigid annular means hingedly attached to the other ends of said arms to be carried thereby; an annular membrane formed from fluid tight, flexible and resiliently stretchable material fluid tightly attached along the outer edge thereof to said annular means and at the inner edge thereof to the peripheral wall of said roof at an elevation lower than the elevation of said annular means, the width of said membrane being greater than the distance between the attached edges thereof so that said membrane extends downwardly from said annular means along the peripheral wall of said tank across the space between the peripheral walls to form with the peripheral wall of the roof an annular trough having a bottom portion below the attached inner edge of said membrane;

65 70 75 granular weighting material filling said trough substantially up to the elevation of said annular means

so that the portion of said resiliently stretchable membrane extending downwardly from said annular means along the peripheral wall of the tank is radially outwardly expanded in tight engagement with said peripheral wall of said tank to form a fluid tight seal thereagainst; and drain means communicating with the interior of said annular trough in the region of the bottom portion thereof for draining rainwater entering said trough from the interior of the same.

2. A fluid tight seal between a peripheral wall of a tank and a peripheral wall of a floating roof of the tank and comprising, in combination, a plurality of arms each hingedly connected at one end thereof to said roof and extending from said attached end toward the peripheral wall of said tank;

a substantially rigid annular means hingedly attached to the other ends of said arms to be carried thereby; an annular membrane formed from fluid tight, flexible and resiliently stretchable material fluid tightly attached along the outer edge thereof to said annular means and at the inner edge thereof to the peripheral wall of said roof at an elevation lower than the elevation of said annular means, the width of said membrane being greater than the distance between the attached edges thereof so that said membrane extends downwardly from said annular means along the pe-

5
